AARON FREYDBERG, OF NEW YORK, N. Y.

PASTE-APPLYING MECHANISM FOR FABRIC-SLITTING MACHINES.

1,271,885.

Specification of Letters Patent. Patented July 9, 1918.

Application filed September 13, 1917. Serial No. 191,199.

To all whom it may concern:

Be it known that I, AARON FREYDBERG, a citizen of the United States, residing at New York, in the county of New York and State of New York, have invented new and useful Improvements in Paste-Applying Mechanism for Fabric-Slitting Machines, of which the following is a specification.

This invention relates to mechanism for applying paste or adhesive to the edges of strips of fabric as the latter are cut from a bolt or roll of material by means of a fabric slitting machine.

At the present time, in making ribbons, bands, tapes and the like, it is the practice to resort to the use of a slitting machine embodying a plurality or gang of cutters, usually in the form of spaced disks, which divide or sever the relatively wide fabric web into relatively narrow strips as such web is drawn off from an unwinding roll and wound on a take-up roll. But it has been found that the severing and loosening of the threads, strands or fibers, which constitute the marginal edges of the strips, will ultimately result in the unraveling and fraying of these edges, thus impairing the value of the product, and in some instances spoiling the same to such a degree as to detract from its salability.

To obviate this disadvantage I have devised a mechanism for use in conjunction with the slitting machine and through the agency of which mechanism a paste or adhesive may be applied to the edges of the fabric strips during the cutting operation, thus effectively uniting and sealing the loose or severed ends of the threads or strands lying at the edges of the strips, and consequently preventing the subsequent unraveling or fraying of these edges.

Another object of the invention is the provision of a pasting mechanism embracing a plurality of pasting elements for operation in conjunction with a gang of fabric cutters, these elements being constructed and arranged independently of each other, so that each may be assembled and dismounted or shifted and adjusted to suit specific conditions of work irrespective of its companion elements.

It is also my purpose to provide a pasting mechanism of this character which will embody the desired features of simplicity, efficiency and accuracy, and which may be

manufactured, installed and operated with but little expense.

With the above recited objects and others of a similar nature in view my invention consists in the construction, combination and arrangement of parts set forth in and falling within the scope of the appended claims.

In the accompanying drawing:

Figure 1 is a view, partly in elevation and partly in section, and showing my invention in conjunction with so much of a fabric slitting machine as is necessary for a clear understanding of its purpose.

Fig. 2 is a perspective view of my pasting mechanism, only one member of the gang of paste applying disks being shown.

Fig. 3 is a detail view in vertical section of a wall of the paste tank showing one of the adjustable shoes thereon.

Fig. 4 is a sectional view taken through one of the pasting disks.

Fig. 5 is a detail perspective view of a section of a fabric strip cut on the machine.

Fig. 6 is a detail sectional view showing the operating of cutting the strip from the fabric web.

Fig. 7 is an enlarged detail view of a modified form of paste applying mechanism.

Referring now to the accompanying drawing in detail the letter A indicates the unwinding or feed roll from which the fabric web B passes to the cutter roll C where it is slit into strips, as hereinafter described, and is then wound on the take-up or rewinding roll D.

This take-up or rewinding roll D may be considered as forming the drive shaft of the mechanism shown in Fig. 1, and such take-up roll is driven in any suitable and well known manner, or by any well known form of power mechanism. As it rotates, it draws the web off the roll A and over the cutter roll C, which latter also revolves in the manner of an ordinary idler roll. The frictional contact of the cutter roll C and the traveling web B against the periphery of the cutting disks 1 will cause the latter to turn, and as these cutting disks 1 also frictionally contact with the paste applying disks or wheels 16, the latter will be also turned in the bath of paste, the direction of rotation of the cutter roll C, the cutting disks and the paste applying wheels being

indicated by the arrows in Fig. 1. The slitting of the web at the cutter roll C, is accomplished by means of a gang of cutting disks, such as are shown at 1, each cutting disk being mounted as at 2 at the forward end of a tilting bar 3, pivotally mounted at 4 in the bearing block 5, which in turn may be adjusted longitudinally of the supporting bar 6 by means of the set screw 7, 10 as will be readily understood by reference to Fig. 1. The rear end of each tilting bar 3 is provided with a leaf spring 8 against which bears the adjustable tension screw 9 carried by the bracket 10, this arrangement 15 of course being for the purpose of applying the requisite tension to the tilting bar 3 to hold its cutter disk in proper relation to the cutter roll C and the web to be slit.

As each cutter disk revolves in the cutting 20 operation it is my purpose to apply a thin line of paste to the peripheral cutting edge thereof, and this I accomplish through the pasting mechanism which is indicated as an entirety by the letter E. As will be best understood by reference to Figs. 1 and 2, this 25 pasting mechanism comprises an elongated paste-holding tank 11, in which the paste P is placed. This tank is formed with a relatively high, longitudinally extending wall 30 12, the top edge of which is provided with a rounded bead 13. This beaded wall is adapted to act as a support and fulcrum for the paste-applying elements, which correspond in number to the number of cutters 35 employed on the machine. Each paste-applying element or member includes, in the present instance, a rocking bar 14, slotted as at 15 for the reception of the paste-applying disk or wheel 16. At one end of this slot 40 is a depending arm 17 carrying a curved paste-scraping blade 18, which is preferably in the nature of a small leaf spring of brass or other suitable metal, and is intended to have its free end lie in juxtaposition to the 45 paste-applying disk to scrape or remove any surplus paste therefrom. Approximately midway its length each bar 14 is provided with a second slot 19 into which fits a positioning shoe 20, which acts to confine or 50 hold the bar 14 in its proper and selected position on the wall 12, when such bar is mounted on the latter. Each bar is loosely mounted or hung on the bead 13 of the wall by allowing the bead to seat in the open- 55 ended vertical slots 21, which are positioned at and communicate with the slot 19. Each positioning shoe 20 is in the form of a small disk slotted as at 22 to slide on the bead 13 of the wall 12, the disk or shoe having a 60 spring tongue 23 the free end of which bears against the wall 12 and frictionally holds the shoe in the position in which it has been set. Of course there is a shoe for each pasting element, and these shoes may be shifted 65 or adjusted along the length of the wall as

may be desired, or removed if necessary without interfering one with the other. At the end of each bar 14 is a weight 24 which is intended to hold the periphery of the paste disk in contact with the cutting edge 70 of the cutting disk which is companion thereto so that as each cutter disk revolves in the cutting operation it will contact with and receive a thin line or film of paste from its similarly revolving paste-applying disk 75 or wheel. The scraper blade 18 of each paste-applying disk may be adjusted as to tension by means of a set screw 25 which is threaded in the arm 17 at the end of the bar 14 and bears against the scraper blade 80 as shown in Fig. 1.

From the above description taken in connection with the accompanying drawing it will be understood that as the web B travels around the cutter roll C and in contact with 85 the cutter disks 1 it is slit by the latter and the paste which has been applied to the cutter disks by the paste-applying disks 16 will in turn be transferred or applied by the cutter disks to the edges of the strips thereby sealing and uniting the cut or severed 90 ends of the threads of strands. It will further be noted that each paste applying element may be readily hung upon and lifted 95 from its supporting bead without interfering with the other elements of the gang, and that by merely sliding or shifting the shoes longitudinally on the bead the distance between the elements may be regulated to conform to the width of the strips to be cut, or 100 in other words the paste-applying elements may be adjusted to conform to the adjustment of the gang of cutter disks.

In Fig. 7 I have shown a slightly modified form of paste-applying device, in this case 105 the weight 24' being made integral with the end of the bar 14' instead of being a separate weight suspended therefrom as is shown in Figs. 1 and 2.

While I have herein shown and described 110 a preferred embodiment of my invention I wish it to be understood that I do not confine myself to all the precise details of construction herein set forth by way of illustration, as modification and variation may be made 115 without departing from the spirit of the invention or exceeding the scope of the appended claims.

What I claim is:

1. The combination with a support over 120 which a sheet is adapted to travel and a cutter for slitting the sheet, of a removable, rotating paste-applying disk in contact with the cutter for applying paste to the latter whereby the paste will be transferred 125 by the cutter to the edges formed in slitting the sheet.
2. The combination with a support for a sheet to be slit into strips, of a rotary cutter for slitting the sheet, and a rotary paste ap- 130

- plying member contacting with the cutter for applying paste to the latter.
3. The combination with means for slitting a sheet, including a rotary cutting disk, 5 of a rotary paste-applying disk contacting with the cutting disk for applying paste to the periphery of the latter, and means for supplying paste to the paste applying disk.
4. The combination with means for slitting a sheet, including a rotary cutting disk, 10 of means for applying paste to the disk, said means comprising a supply tank for the paste, a positioning shoe mounted on the tank, a carrier bar also mounted on the 15 tank and held against lateral movement by the shoe, and a paste-applying member carried by the carrier bar and extending into the tank and adapted to contact with the cutting disk to apply paste to the latter.
- 20 5. The combination with means for slitting a sheet, including a rotary cutting disk, of means for applying paste to the cutting disk, said means comprising a supply tank for the paste, a positioning shoe slidably 25 mounted on and frictionally held in position on a wall of the tank, a slotted bar fitting over and held against lateral movement by the shoe, said bar being mounted to rock on the wall of the tank, a weight at one 30 end of the bar, a rotary paste-applying disk mounted adjacent the opposite end of the bar and extending into the tank to receive paste therefrom and adapted to contact with the cutting disk to apply paste thereto, and 35 means for removing surplus paste from the paste-applying disk.
6. The combination with means for slitting a sheet into strips, including a gang of spaced cutters, of means for applying paste to the cutters whereby said paste will be 40 transferred to the edges of the strips formed in the slitting of the sheet, said means comprising a tank for containing the paste, a plurality of carrier bars mounted to rock on a wall of the tank independently of each other, 45 said bars being loosely hung on the wall, independently adjustable positioning members slidably mounted on the wall and adapted to confine the bars against lateral movement on the wall, a paste applying disk carried 50 by each carrier bar and adapted to contact with a companion cutter to apply paste thereto, the paste applying disks depending into the tank, and tension means connected 55 with the carrier bars for holding the paste applying disks in contact with the cutters.
7. The combination with means for slitting a sheet into strips, including a gang of spaced cutting disks, of a paste holding tank mounted adjacent the cutting disks, and a 60 gang of independently adjustable paste applying disks movably mounted on the tank and adapted to project thereinto to receive paste, and means for holding each of said 65 paste applying disks in contact with the periphery of a companion cutting disk to apply paste to the latter whereby said paste will be transferred to the edges of the strips formed in the cutting or slitting of the sheet.

In testimony whereof I have hereunto set 70 my hand.

AARON FREYDBERG.
